UNITED STATES PATENT OFFICE.

STILLWELL R. HAROURT, OF CHICAGO, ILLINOIS.

PLAYER-PIANO MECHANISM.

1,316,573.

Specification of Letters Patent. Patented Sept. 23, 1919.

Application filed August 25, 1915. Serial No. 47,239.

To all whom it may concern:

Be it known that I, STILLWELL R. HAROURT, a citizen of the United States, residing at Chicago, in the county of Cook and

5 State of Illinois, have invented a certain new and useful Improvement in Player-Piano Mechanism, of which the following is a full, clear, concise, and exact description, reference being had to the accompanying 10 drawings, forming a part of this specification.

My invention relates to piano players, or player-pianos, and is concerned particularly with such instruments that are operated 15 pneumatically, at least so far as the progression of the usual music-sheet is concerned.

In devices of this kind, a so-called "take-up" roll is provided, and with that 20 roll a spool carrying a sheet of music is associated. A pneumatic motor is provided to operate either the spool or the roll, in rewinding or playing, respectively; and my invention is concerned with the control of this 25 pneumatic motor. More specifically, my invention is concerned with the control of the motor during the playing operation, that is, while the motor-power is applied to the take-up roll.

30 It is well known that a pumper-bellows is provided in devices of this kind for the purpose of exhausting the air, by successive impulses, from a so-called "reservoir", which in turn is connected with the devices to 35 which suction is to be applied, the reservoir being provided so that the suction upon the devices to be operated may be steady and continual. An air line connects this reservoir with the motor, and in the prior art it 40 is the practice to interpose a governor in this air line, so that the motor may operate at a constant rate of speed, determined by a preliminary adjustment.

45 My invention is concerned with phrasing the music. That is, it is concerned with means for temporarily retarding or accelerating a phrase in the music being played, entirely independently of the governor control, so that it is possible to quicken the pace 50 of the music for a moment, or to retard it, in order to get the most artistic effect, without interfering with the rate at which the piece of music as a whole is set to be played.

55 My invention is of such a nature that it may readily be applied to any player piano, and, physically, involves the employment of

a valve-box which provides for closing off the flow from the motor and also for temporarily shunting the governor which has been referred to. 60

Other features of my invention will become clear as this description proceeds.

My invention is illustrated in the accompanying drawings, in which:

Figure 1 is a front elevational view of a 65 player piano embodying the features of my invention, parts of the casing being removed in order to reveal the interior construction;

Fig. 2 is a sectional view on an enlarged scale, showing the valve-box and controlling 70 mechanism of my invention;

Fig. 3 is a sectional view taken on the plane of the line 3—3 of Fig. 2 and looking in the direction indicated by the arrows;

Fig. 4 is a sectional view taken on the 75 plane of the line 4—4 of Fig. 2 and looking in the direction indicated by the arrows;

Fig. 5 is a plan view of one of the controlling buttons, which will be referred to; and Fig. 6 is an enlarged vertical sectional 80 view taken on the line 6—6 of Fig. 1.

Referring, first, to Fig. 1, it will be seen that there is illustrated a piano casing 6, the key-board being shown at 7. Properly mounted in the lower part of the casing 85 is a supporting-board 8, which carries the pumper-bellows 9 and 10, operated by the pedals 11^a and the connected reservoirs 11 and 12, respectively. The passageway 13 connects the bellows 9 and the reservoir 11, 90 and a passageway 14 connects the bellows 10 and the reservoir 12. Each of the reservoirs is provided with a spring 15 to keep it normally distended, and it will now be understood that the suction impulses 95 from the respective bellows cause a steady suction to be maintained by the reservoirs.

The action, with the details of which I am not concerned, is illustrated broadly at 16, and it will be seen that the reservoir 11 100 is connected with the wind-chest of the action by means of the air line 17.

A governor 18 is provided adjacent the reservoir 12, and a passageway 19 connects the interior of the governor with the reservoir. The construction of this governor is well known in the art, and it is sufficient to say that upon its interior the movable board of the governor, which is constructed like a bellows, is provided with a valve 20, 110 which more or less restricts the port 21 of the passageway 19, so that the greater the

suction the greater will be the tendency to close the port, thus compensating, in a complementary way, for increased suction in the reservoir 12. It will thus be seen that, with the inlet to the governor of a determined size, the suction controlled by the governor will remain substantially constant.

A spring 22 tends to keep the governor 10 distended.

In the upper part of the piano casing a rail 23 is mounted, and a roller-box 24 is set upon this rail, this roller-box having mounted therein the music-roll 25, the music-spool 26 and the tracker 27, set in such position therebetween that the paper passing from the spool to the roll may slide over the tracker. A pneumatic motor 28 is also mounted upon the rail 23, and, by 15 means of transmission-mechanism 29, the power of the shaft 30 of the motor is conveyed to either the spool 26 or the roll 25.

Since this invention is not concerned with the rewinding of the music-sheet, I shall 25 assume, for the purposes of this description, that the transmission-mechanism is in such condition that the power of the motor is applied to the roll 25. That is the playing condition.

30 A suction-tube 31 leads from the motor 28 and goes to a valve-box 32, mounted upon the rail 23. For the purpose of clearness, I have omitted the front wall of the valve-box so as to show the interior construction, 35 and I shall describe it more fully presently by reference to the other figures. I may say now that the valve-box has three compartments, 33, 34 and 35. The compartment 33 is connected with the governor 18 by means of an air line 36, in which a valve 40 by 40 is interposed. As shown in Fig. 6 the valve 37 is capable of various degrees of opening or closing and is adapted to remain in any set position, being manually controlled by means of a forwardly extending valve stem 50. By means of a direct air line 38, the compartment 35 is connected directly with the reservoir 12. By "directly" I mean to convey the idea that the air line 50 38 is a path of lower resistance than the air line 36, which includes the governor. The tube 31, which has already been referred to, is connected with the compartment 34. It now will facilitate this description to 55 refer also to Figs. 2 to 5. It will be seen that the compartments 33 and 35 may be connected by means of an opening 39, which, however, is normally closed by a valve 40. The compartments 33 and 34 60 are normally connected by means of an opening 41, which may, however, be closed by a valve 42. These valves, as clearly shown in the drawings, slide in guideways 43, 43, mounted upon the partition 44. The openings 39 and 41, as clearly shown in Fig. 3,

are preferably triangular, so that the opening of one and the closing of the other may be gradual. Each of the valves is provided with a downwardly-extending stem 45, which passes out through an opening in the base of the valve-box, and at its lower end is connected with a swinging lever 46, pivoted at 47 in the back of the key-slip. The other end of each of the levers is provided with an actuating-button, which is exposed through the key-slip. The button 42^a, which operates the valve 42, may have any suitable mounting, but the button 40^a, which controls the movement of the valve 40, has a special mounting, illustrated in Figs. 2 and 5. 70 The button 40^a is pivotally mounted upon its lever 46, at 48, and the opening 49 in the key-slip, through which the button extends, is of such size as to permit a slight lateral play of the button. The upper end of a 85 spring 51 may be secured at 52 to the opposite end of the lever 46, whereby the lever 46 and button 40^a are normally held in the raised position as shown in Fig. 2. The button itself is provided with a notch 90 50, which is to coöperate with a catch 51, secured to the top of the key-slip and so disposed that when the button 40^a is depressed and moved slightly to the right the notch will engage with the catch to hold the 95 button 40^a in its lowermost position against the tension of the spring 51 and to lock it in that position, so that the valve 40 may be kept open without further attention, if desired. 100

The operation of my device will now be clear. A certain tempo being ascribed to a piece of music to be played, the valve 37 is primarily adjusted to correspond to the required rate. This rate, as before explained, is maintained by the operation of the governor 18, since, under normal conditions, the suction is applied to the motor exclusively through the intervention of the governor, the valve 40 being completely 105 closed, and the valve 42 being entirely open. If it is desired to temporarily retard the tempo, the button 42^a is correspondingly depressed and the valve 42 more or less closes the opening 41, completely closing 110 it to stop the motor, if desired. However, immediately upon the release of the button 42^a, the tempo immediately returns to the rate as determined by the valve 37. 115

When, on the other hand, it is desired to 120 accelerate momentarily, the button 40^a is depressed and the valve 40 is opened, thus temporarily transmitting the ungoverned suction of the reservoir to the motor. Here, again, immediately upon the release of the 125 button, the spring 51 closing the valve 40, causes the motor to return to its preliminarily-determined speed. If, as before described, the button 40^a is depressed and then moved slightly to its right, the valve 40 may 130

be locked in its open position, so that it will remain open without further attention on the part of the operator. This throws the governor entirely out of use until the button 5 is again released, and during such period it will be seen that the operator may govern the tempo by his own pumping, as is frequently the case when the operator may, at the same time, be playing some other 10 instrument.

I claim as new and desire to secure by Letters Patent of the United States:

1. In a player-piano, an action, note-sheet mechanism for said action, a pneumatic motor for operating said note-sheet mechanism, a suction reservoir, an air line connecting the motor with the reservoir, a valve chest 15 interposed in said air line, the air line between the valve chest and the reservoir being divided into two independent branches, one 20 of said branches having free and open connection with the reservoir, and a governor interposed in the other branch, and a valve in the valve chest, independently controlling 25 the connection thereof with the motor.

2. In piano player mechanism, an action having a wind chest, note-sheet mechanism for said action, a pneumatic motor for operating said note-sheet mechanism, a suction 30 reservoir, an air line connecting said motor and said reservoir, a governor in said air line, a second air line connecting said motor directly with said reservoir, a manually operated valve in said second air line, a manually 35 operative valve for cutting off both said air lines from the motor, and means for applying suction to said wind chest whether said valve is open or closed.

3. In piano player mechanism, an action 40 having a wind chest, note-sheet mechanism for said action, a pneumatic motor for operating said note-sheet mechanism, a suction reservoir, an air line connecting said motor and said reservoir, a governor in said air 45 line, a second air line connecting said motor

directly with said reservoir, a normally closed manually operated valve in said second air line, a normally open manually operative valve for manually cutting off both said air lines from said motor, and means 50 for applying suction to said wind chest whether said valve is open or closed.

4. In piano player mechanism, an action having a wind chest, note-sheet mechanism for said action, a pneumatic motor for operating 55 said note-sheet mechanism, a suction reservoir, an air line extending between said motor and said suction reservoir, a portion of said air line being divided into two branches, a governor in one branch, a valve 60 in the other branch, and a valve in an undivided portion of said air line.

5. An independently removable valve box for attachment to a pneumatic motor in a player-piano, provided with inlet and two 65 independent outlets connected to the wind chest of the player, one of said outlets being a direct connection, and the other having a governor interposed therein, a valve controlling the inlet, and a valve for shutting off 70 the direct connected outlet from the governed outlet and from the inlet.

6. An independently removable valve box for attachment to a pneumatic motor in a player-piano, comprising three compartments, an inlet for one of the compartments and an independent outlet for each of the others, one of said outlets connected directly to the suction chamber of the player, and the other connected through a governor to said 75 suction chamber, a valve controlling a passage between the inlet compartment and the outlet compartment connected with the governor, and a separate passage between said outlet compartment and a valve controlling 80 said separate passage.

In witness whereof, I hereunto subscribe my name this 18th day of August, A. D. 1915.

STILLWELL R. HARCOURT.
